UNITED STATES PATENT OFFICE.

MATTHEW J. KEEVERS, OF NORTHAMPTON, MASSACHUSETTS.

DEVICE FOR FORMING GOLF TEES.

Application filed August 19, 1927. Serial No. 213,995.

This invention relates to certain novel improvements in a device for forming golf tees from sand or other suitable earthy material.

As is well known to those familiar with the game of golf it is the practice to provide at or adjacent to each hole of the golf links certain equipment, comprising in general a stand for supporting a box for containing wet or moist sand, a water pail or bucket, and a towel, usually hung from the sand box. A player whose turn it is to drive off usually takes a handful of sand from the box and forms a sand tee upon which he places the ball to be driven. In the operation of removing the sand from the box and forming the tee, particles of moist sand adhere to the hand of the player and work beneath the finger nails, so that in order to properly handle the club and to prevent cutting the hand with fine particles of sand, which frequently results from the grip upon the club handle, it is the practice for the player to walk back to the water pail and wash his hands with water and then dry them with the towel. The towel soon becomes soiled not only from the players' drying their hands therewith, but from the players or the caddies washing and drying the golf balls. The water also soon absorbs the fine particles of sand, dirt and other foreign matter, so that it is unfit, from a sanitary standpoint, for handwashing purposes.

Furthermore, the above described operation of making a sand tee tends to cause delays and slow up the game, which is undesirable, particularly where the links are crowded. In addition, this manner of forming the tee renders it practically impossible for the player to make a uniform tee upon every occasion or for every drive, the tee sometimes being formed of greater or lower height than is adaptable for a proper drive.

To obviate the above disadvantages is the purpose of my invention, for with my device the player may scoop or dip from the sand box the desired quantity of moist sand, without having the hand in contact with the same in the box, or such contact, if any there be, will be no more than at the tips of the fingers. Then with the thumb he may pat or press the sand in my device and approaching the tee-off, may deposit the sand on the ground in the form of a compact, well-molded and proportioned tee. Furthermore, my device is so proportioned that all

the tees made therewith will be uniform in size and, particularly as to height, of the dimensions best suited to enable the player to drive the ball on a line, that is, to get the greatest distance, by avoiding driving the ball too high in the air, which occurs when the tee is of great height or along the ground when the tee is too low.

Another advantage incident to my device is that it enables the formation of the tee in the top of which is molded a depression or socket which will hold the ball firmly against accidental dislodgment, and yet will not retard or drag the ball when hit. To further assist in making the proper drive a tee molded with my device has molded therein a groove or gutter communicating with the depression or socket at the top and facing the direction in which the drive is to be made, so that there is no possibility of interference with the ball leaving the tee when struck, and furthermore, such gutter when properly placed as to direction with respect to the green affords a visual guide to indicate to the player his proper stance.

Another object of my invention is the provision of a teeing-off device through the medium of which the tee may be rapidly and uniformly molded thereby obviating delays frequently incident to a player forming a handmade tee. It is also my purpose to provide a tee-forming device which will embody the desired features of simplicity, convenience and efficiency, which may be made of various materials, and may be manufactured and marketed in large quantities at an extremely low cost.

With the above recited objects and others of a similar nature in view my invention consists in the construction, combination and arrangement of parts set forth in and falling within the scope of the appended claims.

In the accompanying drawings—

Fig. 1 is a perspective view indicating the manner in which my tee-forming device is to be employed;

Fig. 2 is a bottom plan view of the preferred form of the device;

Fig. 3 is a vertical longitudinal sectional view taken on the line 3—3 of Fig. 2;

Fig. 4 is a perspective view of a modified form of the device;

Fig. 5 is a view, partly in section, and illustrating the position of the device just after a tee of sand has been formed;

Fig. 6 is a further modification partly in section and partly in elevation;

Fig. 7 is a bottom plan view of the modified form of tee shown in Fig. 6.

Referring now to the preferred forms of the invention illustrated in Figs. 1 to 3, the letter A indicates the device as an entirety.

It comprises a hollow cone-like body section 1 merging at its upper portion into the shank 2, which is closed at the top however as at 3. Within the cone at its narrow end, or at the point of its junction with the shank 2, I provide a rounded or boss-like member 4 extending in the direction of the open or mouth end of the cone, so that when a quantity of sand is pressed into the cone section and then deposited upon the ground as hereinafter described, this boss 4 will form a depression or seat for the ball in the said tee. The whole device A may be stamped, molded, cast, or otherwise formed from a single piece of material, if desired. The lower cone section 1, in its formation, is provided with a groove 5, the walls of which form on the interior of the cone a downwardly slanting rib so that when the sand is molded in the cone the complementary groove will be formed, by the rib, in the tee running from the bottom of the latter up to junction with the tee seat. The walls of this grooved rib extend below the bottom edge 6 of the cone proper, so as to form a leg 7. Likewise, the cone is formed with short legs 8, 9 and 10, which also project below the bottom edge 6 of the cone proper. The result is that the device is formed with the four legs 7, 8, 9 and 10. Preferably legs 8 and 9 lie at opposite sides of the grooved leg 7 and in line with each other, while the leg 10 is at the rear of the cone and in direct line with the center of the grooved leg 7. The purpose of these short legs is to hold the mouth of the cone a short distance above the ground when the sand in the cone is deposited thereon so that the molded sand tee may easily leave the cone when the device is struck against the surface of the ground. Were it not for these short legs it might happen that the mouth of the cone in striking the ground, would be driven in a short distance so that the ground would force the sand back into the cone instead of permitting it to leave the latter. The purpose of arranging the legs on the cone in the positions before described is to insure a suitable support for the device when it is struck against the ground, or to obviate tilting which would tend to form an irregular tee, or in some instances, to break or deform the latter.

The above is a description of the mechanical construction of the preferred form of the device and the manner of using the same will be readily understood, particularly in connection with Fig. 1. The player preferably

grasps the device between two fingers, at the junction of the cone and its shank and scoops or dishes the moist sand from the sand box. Then with the mouth of the cone turned upward presses the sand into the cone with the thumb, and then at the teeing-off place simply strikes the mouth of the cone flat against the ground to remove the tee, and upon lifting the device, a uniformly molded tee such as is shown in Fig. 1, with the depression in the top, and the inclined groove communicating with the depression, will result. In the tee shown in Fig. 1, the ball seat is indicated by the letter s and the vertically slanting groove by the letter g. In depositing the tee upon the ground the device is held so that the groove 5 extends in the direction in which the drive is to be made, so that when the tee is deposited the groove g will face in the direction of the proposed drive. Consequently, when the ball resting upon the seat s is driven from the tee there will be no sand in front of the ball to impede or drag its progress or to accidentally interfere with the trueness of direction of the drive.

In Figs. 4 and 5, I have shown a slightly modified form of the invention. In this instance, the device is preferably moulded from celluloid or any other suitable plastic and the body portion or tee-forming cone section is provided at its mouth with angular legs 11 which project below the rim or edge of the mouth. The top of the cone terminates in a plate 12, the ends of which are bent or turned down at 13 and the sides of which are inwardly curved at 14 so that the plate forms a convenient finger grip.

In Fig. 7 I have shown a still further modified form of the invention. In this case I provide simply a perforated, elongated cone section 15 and having a depression 16 formed in the top of the cone. This form of device may have opposite sides of its lower edge concaved as at 17 so as to provide the flanges to permit the ready removal of the sand tee from the cone as is the function of the legs in the other forms of the invention. If desired this form of cone may also be provided with legs.

It is to be noted that with my device the necessity of the player frequently washing the hands is avoided, and at the same time its uniform and desired height will be molded.

I wish it to be further understood that my device may be made of various materials suitable for the purpose, such as metal, paper, celluloid, synthetic resin or combinations of the latter with suitable filler material, indeed, any material whatsoever adapted for the purpose.

While I have herein shown and described certain preferred embodiments of my invention, I wish it to be understood that I

do not confine myself to all the precise details of the invention herein set forth by way of illustration, as modification and variation may be made without departing from the spirit of the invention or exceeding the scope of the appended claims.

What I claim is:

1. A device for forming a golf tee of sand or other earthy material comprising a cup in which the tee is to be molded, said cup having means associated therewith for forming a groove in the side of the molded tee.
- 10 2. A device for forming a golf tee of sand or other earthy material comprising a cup

in which the tee is molded, said cup having means for forming a seat in the top of the tee, and means for forming a groove in the side of the tee.

3. A device for forming a golf tee of sand or other earthy material comprising a cup in which the tee is molded, said cup having a rounded member for forming a seat in the top of the molded tee and having a rib for forming a corresponding groove in the side of such molded tee.

Signed at New York city, in the county of New York and State of New York, this 13th day of July, A. D. 1927.

MATTHEW J. KEEVERS.
